UNITED STATES PATENT OFFICE

FREDERICK DE ANGELIS, OF WEST ORANGE, NEW JERSEY, ASSIGNOR TO METAL TEXTILE CORPORATION, A CORPORATION OF DELAWARE

KNITTED METALLIC FABRIC

Application filed September 30, 1930. Serial No. 485,397.

This invention relates to an improved metallic fabric, and has reference, more particularly, to a knitted metallic fabric useful for many purposes, as e. g. an abrasive material suitable for pot cloths and scouring pads; as an ornamental fabric for trimmings etc.; as a filtering medium, and for other uses wherein a metallic fabric of durable character or pleasing appearance is a desideratum.

mass of labyrinthic character which easily resists tendency to mat too densely, and is therefore admirably adapted for filtering use.

In the drawing, Figure 1 is a face view of 55 the novel metallic fabric made according to and embodying the principles of this invention; Figure 2 is an enlarged conventionalized plan view of the novel metallic fabric, to show the structural formation of the interlocked loops of carrier cord and metal wire, 60 in relation to the cord sections for supporting the groups of metallic wire coils; and Figure 3 is a view showing a length of initial material from which the novel metallic fab- 65 ric is knitted.

Similar characters of reference are employed in said views, to indicate corresponding parts.

Referring to the drawing, the novel fabric 70 is knitted from a composite thread or material shown in Figure 3, the same comprising a carrier cord *a* (which may consist of any flexible material, such e. g. as cotton or other textile yarn, metallic wire or the like) and a 75 metallic gimping *b*. The metallic gimping *b* may be made of wire of round, angular or flat cross-sectional shape. When, however, the novel fabric is desired to provide abrasive characteristics, it is preferable that said 80 gimping *b* comprise a flat or ribbon-like wire or one of angular cross-sectional shape. Said gimping *b* may be made of any desired kind of metal, for both ornamental and abrasive purposes I have found copper to be desirable, in the one case for the reason that it is bright and colorful, and in the other case because it is comparatively non-corrosive and also tough enough to produce desired scraping effects. The gimping *b* is more or less 85 loosely wound or convolved upon and around the carrier cord *a*, so as to form running coils loosely strung on the latter.

The composite thread or material *a*—*b* above described is fed to a suitable knitting machine, which may be either of the circular type for producing tubular fabric or of the flat type for producing flat fabric. The needles of the machine are spaced apart at such distances as may be desired to separate 100

15 which is more or less loosely gimped or convolved coils of a preferably flat or ribbon-like metallic wire; this material is so knitted that interlocked loops of the carrier cord and associated loops drawn from the coils of 20 metallic wire are formed at desired laterally spaced intervals so as to tie or secure the metallic wire coils in groups against undue movement relative to the carrier cord, thus providing substantially straight carrier cord 25 sections between laterally spaced loops, upon which a plurality of wire coils or convolutions, forming a group thereof, are supported and secured against undue sliding displacement on said cord sections. The knitted material thus characterized possesses a raised 30 curly metallic nap on one face thereof formed by the segregated groups of loose metallic coils, and the material thus formed is soft to the touch, and yet affords an efficient abrasive, since, when pressed and rubbed against 35 a resisting surface, the thus secured and supported groups of coils are not unduly displaced, but are sufficiently held to present a multiplicity of knife-like scraping edges to 40 said surface. From the standpoint of appearance, the secured groups of coils form an attractive surface nap of curly texture, which, when bright metallic wire is employed, either of flat or round cross-sectional 45 shape, affords a scintillating or glittering effect, whereby the metallic fabric may be used in many ways for ornamental purposes. As a filtering material, when the novel fabric is 50 piled or enfolded upon itself, the secured groups of coils provide a resilient interstitial

the vertical rows of interknitted or interlocked loops according to the horizontal length of intermediate coil groups desired to be formed in the finished fabric. In the operation of knitting the composite thread or material $a-b$, the knitting needles engage the carrier cord together with the strand of the metallic gimping, pulling a coil of the latter together with a portion of the carrier cord into a loop-formation, comprising a cord loop a' and a substantially parallel closely contiguous wire loop b' . The loop-formations thus obtained are interknitted together so as to leave, extending between laterally spaced adjacent loop-formations, horizontally extending carrier cord sections a'' upon and around which extend a group of coils b'' . Inasmuch as a metallic loop-portion b' is interlocked with each cord loop-portion a' , and both such loop-portions $a'-b'$ are interknitted and locked to a next vertically adjacent loop-formation, the metallic loop-portions b' act as anchoring ties or knots at the ends of each group of coils b'' , so that the latter are firmly held against undue sliding displacement or deformation relative to the straight carrier cord sections a'' upon which the same are supported, and so that the same present a raised curly nap on one face of the resultant fabric. In forming the metallic loop-portions b' with the cord loop portions a' , substantially but a single coil of the metallic gimping material b is drawn out or distorted to form the tying, knotting or anchoring structure by which the integrity of the groups of coils b'' are maintained in the finished fabric.

Having thus described my invention, I claim:-

40. 1. A metallic fabric, comprising a carrier member having a gimping of metallic material spirally convolved in loose coils around and along the length of the same, said gimped carrier member being knitted to provide interengaged loop-formations each comprising a loop of the carrier member and a loop-portion contiguous thereto drawn out from a coil of said metallic gimping, substantially straight supporting carrier sections extending between horizontally adjacent loop-formations, upon which sections are carried groups of said loose coils, each coil group being segregated from adjacent groups by intervening knitted loop-formations, and said coil groups being anchored against longitudinal displacement from their respective carrier sections by the knitted interlocking engagement of the combined carrier member loops and associated loop-portions drawn from the coils of metallic gimping, all whereby the coil groups are exposed at one face of the fabric to form a raised curly nap thereon.

65. 2. A metallic fabric, comprising a carrier strand having a gimping of metallic mate-

rial spirally convolved in loose coils around and along the length of the same, said gimped carrier strand being arranged in substantially parallel courses, with portions of adjacent courses interlocked together at spaced intervals by knitted loops thereof including contiguous loop portions drawn out from the coils of said gimping, whereby groups of gimping coils are anchored in spaced apart relation against movement relative to said carrier strand throughout the area of the fabric, all whereby the coil groups are exposed at one face of the fabric to form a raised curly nap thereon.

3. A metallic fabric, comprising a carrier strand and a strand of metallic material forming a plurality of groups of coils loosely gimped spirally upon and around said carrier strand, said carrier strand and metallic strand being interknitted together to dispose said coil groups in parallel rows, said interknitted carrier strand and metallic strand forming, at and between the ends of adjacent coil groups combined substantially contiguous parallel loop-forming portions for interlocking engagement with similar loop-forming portions of an adjoining row of coils, all whereby the coil groups are maintained individually segregated one from another and exposed at one face of the fabric to form a raised curly metallic nap thereon.

In testimony, that I claim the invention set forth above I have hereunto set my hand this 23rd day of September, 1930.
